UNITED STATES PATENT OFFICE.

OSCAR F. HABERLAND, OF PHILADELPHIA, PENNSYLVANIA.

UPSETTING EXPLOSIVE TOY.

1,311,887.

Specification of Letters Patent.

Patented Aug. 5, 1919.

Application filed October 23, 1917. Serial No. 198,036.

To all whom it may concern:

Be it known that I, OSCAR F. HABERLAND, a citizen of the United States, residing at 6027 Market street, Philadelphia, in the 5 county of Philadelphia and State of Pennsylvania, have invented a certain new and useful Upsetting Explosive Toy, of which the following is a specification.

The purpose of my invention is to upset 10 a mechanical toy at a predetermined point.

A further purpose is to stop the motor of a blow-up toy promptly after the "explosion."

A further purpose is to trip the retaining 15 latch of a blow-up toy through the same mechanism as is used in stopping the motor.

A further purpose is to utilize an additional part of the stroke of the spring in a blow-up toy for imitating the effects of an 20 explosion.

A further purpose is to so correlate stopping notches for the winding mechanism and distances as to conveniently predetermine the point of explosion.

25 Further purposes will appear in the specification and in the claims.

I prefer to illustrate my invention by but one of the forms in which it may appear, selecting therefor a form which has proved 30 in use to be practical, efficient and inexpensive, and which at the same time well illustrates the principles of my invention.

Figure 1 is a side elevation of the preferred embodiment of my invention.

35 Figs. 2 and 4 are vertical sections through the center of Fig. 1, showing the parts in different positions.

Fig. 3 is a top plan view of the structure of Fig. 1 with some of the parts removed.

40 Fig. 5 is a perspective view of a detailed part.

In the drawing similar numerals indicate like parts.

The body of my toy is shown at 1 as simulating a ship, which for certain parts of my invention may be driven through wheels 2, 45 2, on land, or in the water by a screw propeller 3, in either event being driven by a motor 4 connected with one pair of the 50 wheels and the propeller by any convenient train of mechanism preferably controlled by a governor 5. The motor is wound by key 6.

The motor spring and latch mechanism thereof, are so proportioned to the wheels 55 that each notch of motor wind represents a

definite distance of motor drive, corresponding preferably to feet of distance, so that the operator can predetermine the distance of travel very accurately by the extent to which the motor is wound. The positive 60 stop hereinafter described whereby the motor is checked at the same extent of unwind in each case coöperates to make this result reliable as the winding always starts at the same position of the spring. 65

Upon the upper part of the body of my toy I place loose parts adapted to be thrown from the toy by spring action to simulate the explosion, indicating a variety of these parts at 7, 8, 9, 10 and 11 and locating them 70 upon a preferably thin platform 12; so that all can be thrown by engagement of the spring with this single part.

I prefer to throw the platform and loose parts by a "mouse trap" form of spring 13 75 shown in unwound position in Fig. 4 and in wound position engaged by a catch or latch 14 in Figs. 2 and 3. In order that I may have the advantage of an additional means of trip for the spring 13, I mount latch 14 80 upon or connect it with a ram 15 suitably guided in the toy so as to extend beyond the front of the toy to engage an obstacle and trip the latch, releasing the spring. For convenience in limiting the movement of 85 this ram in both directions I place it in the center at the front but bend it, as at 16, part way back. The bend brings it into the best position with respect to the spring motor parts at the rear. 90

I provide two other means of tripping the latch, one by means of a cord 17, which may be directly connected to it and extend out of the body through an aperture 18. The other is by a motor-tripped dog 19 95 which is so connected as to trip the latch and for this purpose may be mounted directly upon the latch or some connection therewith, as at 20, if desired. This dog is so placed as to be engaged by a projection, 100 such as pin 21, upon some part rotated by the motor, so that the engagement of the projection with the dog will not only withdraw the latch to release the spring 13, but will ultimately check the movement of the 105 motor, always with the parts in the same angular position with respect to each other. It is this reliable stoppage of the motor, in connection with the correlation between the winding subdivisions and the distances 110

traversed which combine to give reliable means of determining the distance traversed for any given winding or to estimate the winding required for any given distance.

5 To still further simulate the appearance of an explosion I have provided for a quick upsetting of the body of the toy when on land through the release of the spring 13, using for this purpose preferably a different portion of the travel of the spring from that

10 by which the parts are "blown up". The most convenient part of the stroke for this is the last half of the movement of the spring.

15 Within the line of travel of the spring I place a rod 22 which is normally held in raised position as seen in Fig. 2 by a light coil spring 23 engaging a collar 24 on the rod and any suitable frame piece 25 for this purpose. During the travel of the spring 13, at any convenient part thereof, here shown as at the end of its stroke, I cause the spring 13 to depress this rod by striking it upon the head 26. As the rod is placed "off center" the effect is to upset the body of the toy immediately.

In operation, the spring 13 is set and is caught by latch 14. The motor spring is wound to the desired extent and the toy is started. It may be tripped prematurely by the ram engaging the obstacle at the front or by the string, in which case the motor will run down until the pin 21 is stopped in its angular travel by the dog 19.

30 35 However, the toy will trip automatically as soon as the pin 21 engages the dog 19 with sufficient force to release the latch and the motor will in that event run but a very short time after the spring 13 has been tripped.

40 45 The effect of tripping the spring 13 will be, first to throw the platform, or floor 12, with the loose parts, up in the air, and next to strike the head of rod 22, forcing the rod down against the floor on which the toy is running and upsetting the toy.

What I claim as new and desire to secure by Letters Patent is:—

1. In a blow-up toy, a body portion, parts 50 thereon adapted to be blown up, mechanism for throwing the parts in the air, and means for upsetting the body portion in its entirety, operated by said mechanism.

2. A toy, a spring thereon, a catch for 55 engaging the spring, tripping means for the catch and upsetting means for the toy, operated by the spring.

3. In a blow-up toy, a body portion, parts thereon adapted to be thrown, a spring engaging the parts to throw them, upsetting means for the body of the toy, engaged by the spring, latch mechanism for holding the

spring in set position and release means for the latch mechanism.

4. In a blow-up toy, a body portion, a 65 spring thereon, a latch for the spring, parts upon the body portion adapted to be engaged and thrown by the spring, a driving motor for the toy and engaging devices between the driving motor and the latch to release the spring and effective subsequently to stop the motor.

5. In a blow-up toy, a body portion, a spring thereon, parts upon the body portion adapted to be engaged by the spring in release movement of the latter, a latch for holding the spring in set position, a driving motor and wheels for the toy, connection between the winding mechanism and the motor adapted to engage them at intervals 80 of angular winding movements and proportioned so that each interval corresponds with substantially the same distance of travel, and engaging devices between the motor and latch, releasing the spring at the same point 85 in the motor travel.

6. In a blow-up toy, a body portion, a spring thereon, parts upon the body portion adapted to be engaged by the spring in release movement of the latter, a latch for holding the spring in set position, a driving motor and wheels for the toy, pawl and ratchet devices on the motor for the winding mechanism thereof proportioned so that each notch corresponds with substantially the 95 same distance of travel, and engaging devices between the motor and latch, releasing the spring at the same point in the motor travel restraining the unwinding movement of the spring by the limit of movement of 100 the latch.

7. In a blow-up toy, a body portion, wheels therefor, parts upon the body portion adapted to be thrown, a spring for throwing the parts, a latch for the spring, releasing means for the latch, and a pin located out of the center line of the body and movable downwardly to upset the body portion, and operated by said spring.

8. In a blow-up toy, a body portion, a 110 spring thereon, a latch for the spring, means for moving the latch to release the spring and bodily upsetting and blow-up features operated during the release movement of said spring.

9. In a blow-up toy, a body portion, parts adapted to be blown up, a spring for throwing the parts, a latch for the spring, a driving motor for the toy, and motor-operated release mechanism for the latch, effective to 120 stop excessive unwinding movement of the motor.

OSCAR F. HABERLAND.
